UNITED STATES PATENT OFFICE.

GEORGE E. SHAW, OF CINCINNATI, OHIO.

PULP-COMPRESSION APPARATUS.

SPECIFICATION forming part of Letters Patent No. 693,570, dated February 18, 1902.

Application filed January 7, 1901. Serial No. 42,354. (No model.)

To all whom it may concern:

Be it known that I, GEORGE E. SHAW, a citizen of the United States, residing at Cincinnati, in the county of Hamilton and State of Ohio, have invented certain new and useful Improvements in Pulp-Compression Apparatus, of which the following is a specification.

The object of my invention is to provide apparatus for manufacturing articles from pulp material of any desired form or shape and of uniform density.

The invention consists of the parts, combinations, and arrangements of parts hereinafter described and claimed.

15 In the drawings, Figure 1 is a vertical section of an apparatus embodying my invention; Fig. 2, a horizontal section on line 2-2 of Fig. 1; Fig. 3, a section on line 3-3 of Fig. 1; Fig. 4, a section on line 4-4 of Fig. 1; Fig. 20 5, an enlarged section on line 5-5 of Fig. 2; Fig. 6, a perspective view of the collapsible lining for the article to be manufactured, and Fig. 7 a perspective view of the parts of the lining shown in Fig. 6.

25 In the drawings I have illustrated apparatus adapted to the manufacture of buckets or kegs; but it will be understood that by changing the form of the parts articles of any desired shape may be formed.

30 Reference-letter A denotes a mandrel, the outer surface of which corresponds to the inner surface of the inverted keg B; C, plungers or pistons having faces corresponding to the outer surface of the sides of the keg; D, 35 a plunger or piston having a face corresponding to the bottom of the keg; E, a frame or spider operatively connected with plungers C and D; F, a piston operating in cylinder f and carrying frame E; G, a table carrying 40 mandrel A; H, a piston-rod carrying table G; J, a cylinder for operating piston-rod H through piston h, and K tie-rods upon which the different parts are mounted.

The mandrel A preferably consists of a partially hollow core a, rigidly attached to table G on piston-rod H and provided with a detachable outside covering a', whose outer surface corresponds with the inner surface of the keg. The outside covering a' preferably 45 consists of three parts a², a³, and a⁴, so fitted together that the part a³ forms a wedge ca-

pable of inward movement and incapable of outward movement relatively to the parts a² and a⁴. (See Figs. 6 and 7.) In order to provide for securing parts a², a³, and a⁴ in position, the mandrel A is provided at the bottom with a flange a⁵ and at the top with T-shaped notches adapted to receive and engage the T-shaped lugs a⁶ on each of the parts. The lugs a⁶ and their notches are so arranged that the upper surface of the lugs and the upper surface of the mandrel are flush and leave no crevices or projections to mar the inner bottom surface of the keg. Surrounding mandrel A and mounted on 55 table c are the plunger compartments or chambers c', in which the plungers C operate on radial lines toward and away from mandrel A. In this case I have shown the apparatus as having four plungers C; but 60 the number may be varied without materially affecting the product. However, I think it will be found that in most cases of articles of a cylindrical nature three or more plungers are desirable. When articles of other shapes 65 are desired, the shape of the mandrel or core A and number and shape of the plungers C will be varied to correspond. The plungers C are operated by toggle-joints c², having the stationary pivotal bearing c³ on table c and 70 the movable pivotal bearing c⁴ in plungers C. In order to render the stroke of the plungers C adjustable, one of the toggle-links is broken and provided with an oppositely-threaded sleeve c⁵ engaging each part, so that rotation 75 of the sleeve will carry the parts toward or away from each other, shortening or lengthening the link. The toggle-joints c² are operated by pivot-block e, sliding on slide-bar e', which is carried by spider E. It will be 80 seen that when spider E is raised or lowered the toggle-joint c² acts to withdraw or press the plunger from and to the mandrel A. Immediately over the mandrel is another plunger-compartment, in which the plunger D is 85 operated directly from spider E through plunger-rod e². At C² this compartment is provided with an opening, through which a supply of the pulp material may be admitted. This opening is preferably in the uppermost 90 portion of the compartment, so that it does not have to withstand the intense pressure re-

sulting when the plunger has nearly reached its downward limit. Plungers C and D are provided with any of the usual draining-faces. In plunger D the draining-chambers communicate with external channel d , which encircles the plunger just above its draining-face and above which the plunger D is made smaller than its compartment, so as to permit the passage of liquids from the channel 5 into the portion of the compartment above the plunger, and vice versa. Near its bottom the compartment is provided with a port d' , normally closed by plug d^2 and communicating with channel d^3 , which leads to the outer 10 edge of the compartment-frame. The plug d^2 carries a spring-arm d^4 , provided with a notch d^5 , engaging guide d^6 and equipped with a spiral spring d^7 , tending to withdraw plug d^2 from port d' . At its inner end the 15 arm d^4 is provided with a flange d^8 , engaging bell-crank lever e^3 , the other arm of which intermittently engages rod e^4 , carried by spider E. The rod e^4 has some longitudinal play in spider E and is so arranged that 20 after the face of plunger D has passed port d' on its downward stroke the end of rod e^4 engages flange d^8 to depress spring-arm d^4 to release notch d^5 from guide d^6 and permit spring d^7 to withdraw plug d^2 and open port 25 d' at the instant when channel d is opposite port d' . This throws channel d into communication with channel d^3 and drains the compartment above the plunger. At its lower 30 end rod e^4 is provided with a pin e^5 , which upon the upward movement of rod e^4 engages bell-crank lever e^3 to throw plug d^2 back to close port d' when it is locked by notch d^5 . 35 Spider E is reciprocated up and down by means of piston F in cylinder f, which is provided with the usual valves and ports for this purpose. At their outer ends arms e^5 of spider E are given a sliding bearing on the rods K to steady their movement.

Mandrel A is mounted on table G, which is 40 carried by piston-rod H. Table G is normally locked in its extreme upward position by swinging arms or props g, which may be withdrawn by means of cord g', passing over pulleys g². Piston-rod H is rendered capable 45 of vertical reciprocation by means of piston h in cylinder J, which is provided with the usual ports and valves for this purpose. Resting on table G immediately surrounding the lower portion of core a and projecting 50 slightly over the edge of table G is a stripping-ring g³, which is notched at g⁴ to engage the bottom flange a⁷ of the core-covering a'. The supporting-frame for arms g carries an annular receiving-table g⁵, provided with a 55 flange g⁶, adapted to engage the projecting edge of stripping-ring g³, but permit table G to pass through it. It will be seen that when the piston h is operated to lower table G stripping-ring g³ engages table g⁵ and strips the 60 covering a', together with the keg B, from mandrel A. To remove the core-covering a', the wedge-shaped part a⁸ is forced inwardly,

which is easily done when core a is removed, whereupon the other pieces a² and a⁴ may be removed.

In operation a supply of pulp material is admitted through opening C². This material is in a comparatively liquid form and flows down into compartments c'. The supply is continued until all the plunger-compartments 70 are filled, when it is shut off. Then steam or other fluid under compression is admitted to cylinder f to cause spider E to descend under pressure. This movement of spider E simultaneously advances plungers C and D toward 75 mandrel A, compressing the material before them. As the compression continues the draining-surfaces of the plungers drain off the liquid in the material, leaving the solid matter to be closely molded about mandrel A. 80 As plunger D advances the liquid passing through its draining-face passes into channel d and thence around the smaller upper portion of the plunger into the compartment above the plunger. When port d' is passed by the compressive face of plunger D, it is opened through the action of rod e^4 on arm d^4 and the liquid permitted to flow out through channel d^3 and down into channel c^9 , whence it is conducted away through opening c^{10} . The liquid in 85 compartments c' is also conducted out through the draining-surfaces on plunger C into channel c^9 and conducted away through opening c^{10} . Owing to the fact that all the plungers are driven from the same spider E the material in each compartment will be subjected 90 to the same pressure and a uniform article will result. The production of a uniform article is assisted by the character of the mandrel, which is practically solid and capable of withstanding intense pressure without 95 breaking or yielding. After the pulp material has been compressed to the form of the keg B the pressure is relieved. Then props g are swung back and table G lowered until 100 receiving-table g⁵ strips the covering a', and keg B with it, from mandrel A. The covering a', which is now the lining of the bucket, is readily removed therefrom by first removing the wedge-shaped part a⁸.

I claim as my invention—

1. The combination in apparatus for compressing pulp, of a central mandrel or core, conforming to the inside surface of the article to be manufactured; plunger-compartments provided with plungers having faces conforming to the outside surface of the article; a motor; slide-blocks connected with the motor; and toggle-joints connected with the slide-blocks, having one of their links given a stationary pivotal bearing, and the other link a pivotal bearing in the plunger, substantially as and for the purpose set forth.

2. The combination in apparatus for compressing pulp, of a central mandrel or core, conforming to the inside surface of the article to be manufactured; plunger-compartments provided with plungers having faces conforming to the outside surface of the article; a mo-

tor; slide-blocks connected with the motor; and toggle-joints connected with the slide-blocks, having one of their links given a stationary pivotal bearing, and the other link a 5 pivotal bearing in the plunger; and means for adjusting the length of the plunger-connected link of the toggle-joints, substantially as and for the purpose set forth.

3. The combination in apparatus for compressing pulp, of a mandrel having its outer surface conforming to the inside inverted surface of the article to be formed; a piston-rod carrying the mandrel from below and provided with a piston and cylinder for reciprocating the mandrel vertically; a cylinder, piston and piston-rod located immediately above the mandrel, and adapted to be actuated to reciprocate the piston-rod; a plunger-compartment located above the mandrel; a 15 plunger on the upper piston-rod operating in said compartment to compress the contents thereof against the top of the mandrel; a series of radiating compartments surrounding the mandrel; plungers in said compartments operating to compress the contents thereof against the sides of the mandrel; and a connection between the upper piston and the plungers for reciprocating them toward and away from the mandrel, substantially as and 20 for the purpose set forth.

4. The combination in apparatus for compressing pulp, of a mandrel having its outer surface conforming to the inside inverted surface of the article to be formed; a piston-rod carrying the mandrel from below, and provided with a piston and cylinder for reciprocating the mandrel vertically; a cylinder, piston and piston-rod located immediately above the mandrel and adapted to be actuated to reciprocate the piston-rod; a plunger-compartment located above the mandrel; a plunger on the upper piston-rod operating in said compartment to compress the contents thereof against the top of the mandrel; a series of radiating compartments surrounding the mandrel; plungers in said compartments operating to compress the contents thereof against the sides of the mandrel; toggle-joints having a pivotal bearing in the plungers 45 and a stationary bearing, and slide-blocks carried by the upper piston-rod and connected with the apex of the toggle-joints, substantially as and for the purpose set forth.

5. In a mandrel for pulp-compression apparatus, the combination of a rigid internal core with a covering for the core made in three or more sections, one of which sections is wedge-shaped to permit its movement inwardly, substantially as and for the purpose set forth.

6. In a mandrel for pulp-compression apparatus, the combination of a rigid internal core having at its bottom a supporting-flange, and at its top, notches; a covering for the core adapted to rest on the supporting-flange and 60 made in three or more sections, one of which sections is wedge-shaped to permit its move- 65

ment inwardly; and lugs on the sections adapted to engage the notches in the core, substantially as and for the purpose set forth.

7. The combination of the vertically-movable mandrel-core *a*; the covering *a'* consisting of sections *a²*, *a³* and *a⁴*; the stripping-ring *g³* and the receiving-table *g⁵*, adapted to engage ring *g³* and strip covering *a'* from the core, substantially as and for the purpose set forth. 70 75

8. In a vertically-disposed compression-compartment for pulp-compression apparatus; the combination of a downwardly-acting compression-plunger; a draining-face for the plunger, passages adapted to convey the liquid passing through the draining-face to the portion of the compartment above the plunger; a port in the compression-compartment; means for throwing the port into communication with the upper portion of the compartment when the plunger has nearly reached the end of its compression-stroke; a plug normally locked in position to close the port; a spring tending to withdraw the plug to open 80 the port; and means connected with the compression-plunger, adapted to release the plug when the plunger has nearly reached the end of its compressive stroke, substantially as and for the purpose set forth. 85

9. The combination of the vertically-movable table *G*; mandrel-core *a* carried by table *G*; covering *a'* on core *a*; piston *h* and cylinder *J* for reciprocating table *G*; props for locking table *G* in position; stripping-ring *g³* and receiving-table *g⁵*, adapted to engage ring *g³* and strip covering *a'* from the core, substantially as and for the purpose set forth. 90 95

10. The combination in pulp-compression apparatus of a vertically-movable mandrel, mounted on a fluid-actuated piston, with means for rigidly locking the mandrel in position independently of the piston, substantially as and for the purpose set forth. 100

11. The combination in pulp-compression apparatus, of a vertically-movable mandrel mounted on a fluid-actuated piston; swing-props adapted to engage the mandrel and rigidly lock it in position, and means for swinging the arms out of operative position, substantially as and for the purpose set forth. 110 115

12. In a vertically-disposed compression-compartment for pulp-compression apparatus, the combination of a downwardly-acting compression-plunger; a draining-face on the plunger; passages adapted to convey the liquid passing through the draining-face to the portion of the compartment above the plunger; a port in the compression-compartment near the bottom; a plug normally closing the 120 125 port; and means connected with the plunger adapted to withdraw the plug after the face of the plunger has passed the port, substantially as and for the purpose set forth.

13. In a vertically-disposed compression-compartment for pulp-compressing apparatus, the combination of a downwardly-acting 130

4
compression-plunger, tightly fitting its compartment at its face, and smaller than the compartment above the face; a draining-face on the plunger; an annular draining-groove 5 in the plunger just behind the face, communicating with the drain-channels in the face, and with the space between the smaller portion of the plunger and its compartment; a port in the compression-compartment near 10 the bottom; a plug normally locked in position to close the port; a spring tending to withdraw the plug to open the port; and means connected with the compression-plunger adapted to release the plug when the annu-

lar groove registers with the port, substantially as and for the purpose set forth. 15

14. In a vertically-disposed compression-compartment for pulp-compressing apparatus, the combination of plunger D having a draining-face communicating with channel 20 d; port d'; channel d³; plug d² carrying arm d⁴; spring d⁷; bell-crank lever e³ and rod e⁴, substantially as and for the purpose set forth.

GEORGE E. SHAW.
